(57) **CLAIM**

The ornamental design for a “recyclable hanger,” as shown and described.

DESCRIPTION

FIG. 1 is a top, front, and left side perspective view showing our new design for a recyclable hanger.

FIG. 2 is a front view of the recyclable hanger shown in FIG. 1, the rear view being a mirror image thereof.

FIG. 3 is a top view of the recyclable hanger shown in FIG. 1.

FIG. 4 is a bottom view of the recyclable hanger shown in FIG. 1.

FIG. 5 is a left side view of the recyclable hanger shown in FIG. 1; and,

FIG. 6 is a right side view of the recyclable hanger shown in FIG. 1.

1 Claim, 4 Drawing Sheets
